CARRIER FOR PHOTOGRAPHIC PLATES
AND FILMS

George D. Pappajien, Danielson, Conn.

Application February 19, 1936, Serial No. 64,756

6 Claims. (Cl. 95—100)

This invention relates to an improved hanger by means of which a photographic plate or film may be suspended in a tank or equivalent container filled with developing fluid and one object 5 of the invention is to provide a device of this character having the form of an open frame adapted to fit about marginal portions of a plate or film with both faces of the plate or film exposed so that they may be acted upon by the 10 developing fluid when the frame is suspended in a developing tank.

Another object of the invention is to so form the frame that while a plate or film may be easily fitted into the frame, it will be prevented 15 from accidentally slipping out of place and thus eliminate likelihood of a plate dropping upon a floor or workbench and becoming broken and likewise eliminating likelihood of a wet film dropping upon the floor or workbench where it will 20 be soiled by dust, dirt and other foreign matter.

Another object of the invention is to provide a frame of this character which may be formed of companion sections fused or otherwise firmly secured to each other so that all portions of the 25 frame will be permanently united and thus prevented from separating and allowing a plate or film to drop out of the frame.

Another object of the invention is the provision of a frame which may be formed of blown 30 celluloid, thus producing a frame which will be of light weight but of sufficient strength to carry a plate or film and not be liable to be damaged by the action of acid in the developing fluid.

The invention is illustrated in the accompanying 35 drawing, wherein:—

Figure 1 is a view showing a plate and film carrier of the improved construction suspended in a developing tank shown in section.

Figure 2 is a view in elevation looking at the 40 improved frame from the right of Figure 1.

Figure 3 is a view in elevation looking at the opposite face of the frame from that shown in Figure 1.

Figure 4 is a sectional view taken vertically 45 along the line 4—4 of Figure 1.

Figure 5 is a sectional view taken horizontally through the frame, along the line 5—5 of Figure 1.

Figure 6 is a fragmentary perspective view of 50 a corner portion of the frame, and

Figure 7 is a fragmentary perspective view of the intermediate portion of one end portion of the frame.

This improved carrier for a photographic plate 55 or film is in the form of a frame having upper

and lower bars 1 and 2 connected by end bars or strips 3 and 4. Marginal portions of the upper and lower bars and side or end bar 4 are projected forwardly to form flanges 5 which define shoulders 6 for engagement by marginal edges of a photographic plate or film mounted in the frame. These flanges also serve as carriers for facing strips 7, 8, 9 and 10 and upon referring to Figures 4 and 5 it will be seen that portions of the facing strips project inwardly beyond the flanges 10 in spaced relation to inner marginal portions of the side and end bars of the frame and, together therewith, define a channel extending about the inner periphery of the frame to receive marginal portions of a plate or film. The facing strips 7, 15 8 and 9 are each of an even width throughout its length but the spacing strip 10 has extensions or arms 11 projecting inwardly relative to the frame so that the side extensions or arms 11 may be secured against the flanges of the upper and 20 lower bars of the frame and firmly mount the facing strip 10 in spaced relation to the side bar 3 of the frame for practically the entire length thereof and define an entrance slot or passage 12 through which a photographic plate or film is 25 passed into the frame. Ribs 13 and 14 are formed upon confronting faces of the end bar 3 and facing strip 10, and upon referring to Figures 2 and 6 it will be seen that these ribs are 30 gradually reduced in thickness towards their inner ends and are of less width than the end bar and facing strip. By having the ribs gradually reduced in thickness towards their inner ends, a photographic plate may be easily forced inwardly through the passage 12 by having a corner 35 portion first thrust inwardly between the inner ends of the ribs and tilting movement then imparted to the plate to dispose it in proper alignment with the frame and exert force which will spring the facing strip 10 away from the end bar 40 of the frame. Pressure may then be applied to the plate to force it inwardly of the frame and fully into the frame. As the plate moves inwardly out of engagement with the sloping faces of the ribs 13, the facing strip 10 returns to its normal position in which it is parallel to the end bar 3 and the ribs will serve as abutments to prevent the plate from accidentally slipping out of the frame. The facing strip and end bar may, however, be sprung apart a sufficient distance to 50 permit removal of the plate after it has been developed. As additional means for preventing the plate from accidentally slipping out of the frame through the passage 12, the end bar 3 and the facing strip 10 are struck from their outer 55

marginal side edges intermediate their ends, as shown at 15, to form ears 16 which are undercut at their ends and serve as cleats to receive a binder, such as a rubber band or piece of string. The cleats or ears and the intermediate portions of the end bar and facing strip will be drawn toward each other when the rubber band or string is wound about the ears and the facing strip and end bar of the frame will have binding engagement with the portion of the photographic plate disposed between them. It should also be noted that portions of the rubber band or string extend across the space between the end bar and facing strip, as clearly shown in Figure 2, and will serve very effectively as a barrier to prevent outward movement of the photographic plate. Slots 18 and 19 are formed in the bars 1, 2, and 3 of the frame and the facing strips 7, 8, and 9 carried thereby to permit the bordering channel to be easily cleared of sediment. Grooves 20 and 21 are formed in outer faces of the side and end bars of the frame and the facing strip 10, it being understood that grooves similar to the groove 21 may also be formed in the remaining facing strips, if so desired. These grooves reduce the weight of the frame and also reduce likelihood of the frame slipping out of a person's hand. In order to support the frame in a tank 22 of developing fluid, the upper bar 1 carries upwardly extending arms 23 which preferably converge upwardly although not necessarily so and at their upper ends carry a cross bar or yoke 24 which is of greater length than the frame and at its ends terminates in depending heads 25 which are adapted to rest upon the ledges 26 of the developing tank and suspend the frame in the tank. By having the heads hook-shaped to provide bills 27, the frames may be suspended from an overhead wire where they will dry after being used.

Having thus described the invention, what is claimed as new is:

1. A carrier for photographic plates and films comprising an open frame having side and end bars, the side bars and one end bar being formed with bordering flanges, facing strips secured against the bordering flanges with their inner marginal portions projecting from the flanges and together with inner marginal portions of the side bars and end bar defining a channel about the inner periphery of the frame, the remaining end bar of the frame and a facing strip disposed opposite thereto being spaced from each other to provide an entrance for insertion of a plate or film into the frame, ribs extending longitudinally of end portions of the last-mentioned end bar and facing strip and tapered longitudinally toward their inner ends, the ribs being of less width than the side bar and facing strip carrying the same and terminating in spaced relation to inner marginal edges thereof whereby the ribs constitute abutments to retain a film or plate in the frame, and means for suspending the frame in a developing tank.

2. A carrier for photographic plates and films comprising an open frame having side and end bars, facing strips carried by the side and end bars and having portions spaced from opposed

portions of the frame to form a channel about the inner peripheral edge of the frame to receive marginal portions of a plate or film, one end bar of the frame and an opposed facing strip being spaced from each other for substantially the entire length of the end bar to provide an entrance, a rib carried by the last-mentioned end bar and extending longitudinally of one end portion thereof, a rib carried by the opposite end portion of the last-mentioned facing strip and extending longitudinally thereof, said ribs gradually decreasing in thickness towards their inner ends and being of less width than the end bar and facing strip and constituting cams whereby the end bar and facing strip may be sprung away from each other as a plate is slid into the frame, the ribs also serving as abutments for engaging a marginal edge of a plate within the frame and maintain the plate in the frame, and means for suspending the frame in a developing tank.

3. A carrier for photographic plates and films comprising an open frame having side bars and one end bar formed with marginal seats about their inner peripheries, the other end bar of the frame being formed with a longitudinally extending slot whereby a plate or film may be slid into the frame, ribs carried by walls of the slot and constituting cams engageable by a plate to expand the slot during the insertion of a plate, the ribs also constituting abutments for engaging an end of a plate to maintain the plate within the frame, and means for suspending the frame in a developing tank.

4. A carrier for photographic plates and films comprising an open frame formed about its inner periphery with a bordering channel to receive marginal portions of a plate or film and support the same in the frame, the frame being formed of yieldable material and at one end having a slot constituting an entrance for insertion and removal of a plate or film, abutments in the slots extending from inner faces of opposed walls of the slot in spaced relation to each other longitudinally thereof and partially blocking the slot to prevent accidental movement of a plate or film out of the frame through the slot, and means for suspending the frame in a developing tank.

5. A carrier for photographic plates and films comprising an open frame formed of yieldable material and having an entrance slot at one end and a bordering channel about its inner periphery constituting a seat for marginal portions of a film or plate, and abutments at the slotted end of the frame partially blocking the slot to prevent premature movement of a plate or film out of the frame through the slot.

6. A carrier for photographic plates and films comprising an open frame having an entrance slot at one end and formed with a channel about its inner periphery constituting a seat for marginal portions of a plate or film, walls of the channel being formed with openings to facilitate cleaning of the channel, and means at the slotted end of the frame to prevent premature movement of a plate or film out of the frame through the slot.

GEORGE D. PAPPAGION.
